UNITED STATES PATENT OFFICE.

ROBERT G. CALLUM, OF WASHINGTON, DISTRICT OF COLUMBIA.

AUTOMATIC FIRE AND BURGLAR ALARM TELEGRAPH.

SPECIFICATION forming part of Letters Patent No. 758,736, dated May 3, 1904.

Application filed March 1, 1902. Serial No. 96,223. (No model.)

To all whom it may concern:

Be it known that I, ROBERT G. CALLUM, a citizen of the United States, residing at Washington, District of Columbia, have invented 5 certain new and useful Improvements in Automatic Fire and Burglar Alarm Telegraphs; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention, which relates to automatic fire and burglar alarm telegraph systems, contemplates the production of an efficient and durable instrument combining in a compact structure improved means connecting a local 20 or house wire, floor-section wires, and a main-line wire, all in normally closed metallic circuit with an annunciator, an alarm-bell, and a battery-signal, whereby any disturbance occasioned by fire or unlawful tampering with 25 the wires or by exhaustion of the batteries is promptly made known to the occupants of the building affected and to the central office in a manner to announce to all concerned the exact locality and nature of such disturbance. 30 The floor-sections are each connected by a metallic circuit with the instrument, and as another feature of the invention there is provided, preferably in the house-circuit, a relay which is operated coincidently with the unlawful looping out or grounding of any of 35 the floor-section circuits to sound a distinctive signal.

Other features of the invention, together with the advantages possessed thereby, are 40 set forth in the following detailed description, in connection with which attention is called to the accompanying drawings, illustrating the preferred form of instrument and parts coöperating therewith.

45 In the drawings, Figure 1 is a front elevation of an automatic fire and burglar alarm instrument embodying the invention. Fig. 2 is a front elevation of the instrument with the cap or cover removed and showing the 50 connections. Fig. 3 is a rear elevation. Fig.

4 is a bottom view. Fig. 5 is a top view. Fig. 6 is a detail view in perspective showing the means for controlling the locating-signals. Fig. 7 is an enlarged view in perspective of the means for producing a short circuit upon 55 the breaking of any of the floor-section circuits. Fig. 8 is a vertical sectional view on line 8 8 of Fig. 5.

Referring to the drawings by numerals, 1 denotes the back plate, of insulating material, 60 which supports the mechanisms, including a bell 2, preferably secured to an extension 3 of the back plate. A train of gearing impelled by a coiled spring is mounted between frame-plates 4 5, and to the escapement 6 of 65 the train is secured the arm 7 of a bell-hammer 8. Secured also to the escapement is an arm 9, arranged to be normally engaged to lock the train by a trip 10 on an armature 11. A pair of magnets 12 12, fixed to the back 70 plate, have their pole-pieces 13 extended outwardly to normally attract the armature and lock the train, the armature being pivotally secured to a bracket 14 on one of the pole-pieces. The armature is arranged to fall by 75 gravity to release the train when the magnets become deenergized, the limit of movement being fixed by a stop-screw 11'.

On a central shaft 15, which preferably is driven directly by the mainspring of the gearing, is mounted an arm 16, carrying a handle 17, by which the spring is wound, and provided at its free end with a pointer 18. Fixed to the shaft to the rear of the arm 16 is a plate 19, which in the rotation of the shaft 80 is brought successively into engagement with a concentrically-arranged series of contacts fixed to a curved support 20, of insulating material, the support being secured on the outer frame-plate 4. Each of the contacts consists 85 of two spring-arms 21 22, fixed at their inner ends in slots in the support and having their normally separated outer ends in the path of the plate 19, whereby the latter in its movement operates by engagement to press the 90 ends of the arms into contact with each other, and thus produce a short circuit in the manner presently to be described.

By reference to Figs. 1 and 2 of the drawings it will be observed that the instrument 100

is adjusted for use in a building having five floors, although obviously the number may be increased or diminished. The contacts for the floor-signals are interposed between the 5 initial or "set" position of the handle-arm 16 and the position thereof which indicates the exhaustion of the battery. In adjusting the instrument for service the handle-arm is turned to the set position and is, together 10 with the train of gearing, locked by the trip 10 on the armature, the latter being attracted by the magnets.

On the back plate are binding-screws, certain of which are connected by wires with 15 the contacts on the support 20. The wire 23, which is connected with the first screw 24, leads to the arm 21 of the first pair of contacts, and leading from the second screw 25 is a wire 26, which connects with the arm 22 20 of the first pair of contacts and also with the arm 21 of the second pair, the first arm 22 and the second arm 21 being lapped at their inner ends, as shown more clearly in Fig. 7. Wires 27, 28, and 29, respectively, lead from 25 screws 30, 31, and 32 to the lapped arms 22 21 of the other contacts. A wire 33 connects the binding-screw 24 to a binding-screw 34, to which is connected by a binding-post one end of the house or building circuit-wire 35. 30 The other end of the house circuit-wire is connected by a binding-post with a screw 36, which is connected with one of the magnet-wires 37. Binding-posts, which are connected with the binding-screws, are provided at the 35 rear side of the back plate, and connected with the posts are the floor circuit-wires, which are shown in Fig. 2. The wire 39 of the first-floor section leads from the screw to the section and back to the screw 25. The second-floor-section wire 40 leads from the screw 25 to the section and back to the screw 30. The third-section wire 41 leads through the section and back to the screw 31. The fourth-section wire 42 leads through the section and 40 thence to the screw 32, and, finally, the fifth-floor-section wire 43 leads to the final spring-contact 22. 38 is the other magnet-wire, which connects with the wire 43.

In the house circuit-wire 35 is a battery 44 50 and also a double-balanced relay 45, the function of which is to sound an alarm and announce disturbance occasioned by unlawful looping out or grounding of any of the floor-section wires or by weakening of the battery. Distinctive signals are provided in connection 55 with the relay to announce whether the disturbance is due to an increased or diminished resistance in the circuit-wires.

When a break occurs in any of the normally closed floor-circuits, the magnets become deenergized and the armature falling by gravity unlocks the train of gearing, setting it in motion to revolve the handle-arm 16 and plate 19. As the plate engages the contact- 65 arms 21 22 the outer ends of the arms are

moved against spring action into contact with each other to short-circuit the floor-section wire to which they are connected. This short circuit results in the energizing of the magnet, whereby the armature is attracted 70 and moved to lock the train and the handle-arm. Obviously if the break occurs in the upper floor-sections the plate 20 will traverse the contacts in advance of the pair connected with the disturbed section without closing the 75 circuit; but when the contacts of the affected section are engaged by the plate and brought together the circuit is established and the mechanism is stopped with the arm 16 at the point which indicates the locality of the disturbance. The length of the plate 19 is such as to extend between all of the contacts, whereby the engagement of the contacts is maintained throughout the entire movement of the plate. If the battery becomes exhausted, the circuit is broken and the arm moves to the position which indicates this character of disturbance.

Referring to Figs. 1 and 4, a dial-plate 46 is shown mounted in a removable cap or cover 47, the dial-plate having thereon in the path of the pointer 18 the floor-numbers, the set position of the arm, and the position of the arm when the battery has become exhausted. The instrument is connected with a main-line 90 wire leading to the central office, in which line is located a tap-bell and recording instrument. The main-line wire 48 leads at one end to a binding-post connected with a binding-screw 49 on the back plate, and the other 100 end of the wire leads to a binding-post connected with a binding-screw 50. A wire 51 connects the screw 49 with a screw 52 on the frame-plate 4, and a wire 53 connects the screw 50 with a spring-contact arm 54, fixed 105 to a block 55 on the support 20, the block being of insulating material. The arm 54 is arranged between contact-arms 56 57, also fixed to the block 55 and having their outer ends bent in the direction of the middle arm 54. 110

On a shaft 58, which receives motion through the train of gearing, are fixed two make-and-break wheels, one of which, 59, is notched in its periphery to send a building-signal, and the other, 60, is notched to transmit the floor-signal. Secured to a block 61 of insulating material is a brush 62 in contact with the wheel 59 and also a brush 63 in contact with the wheel 60. The brush 62 is connected by a wire 64 with the contact-arm 56, and a wire 65 connects the brush 63 with the contact-arm 57. Normally the arms 54 and 56 are in contact, and a circuit is established with the main line to send when the mechanism is set in motion a building-signal by the wheel 59. The 125 wheel 59 is provided with duplicate notches, and the wheel is geared to complete a revolution while the arm 16 is moving to the first pair of contacts 21 22, whereby two building-signals are sent to and recorded at the central 130

office. The building-signals are followed by a signal which locates the floors of the building in which the disturbance is created, this being accomplished through the medium of the wheel 60 in the following manner: On the shaft 15 is fixed a cam 66, which in the normal position of the parts is in the path of an insulated projection 67 on the middle contact-arm 54, whereby the latter is forced against spring action out of contact with the arm 57, which connects with the floor-signal wheel, and into contact with the arm 56, which connects with the building-signal wheel. In the initial movement of the parts the contact of the arms 54 56 is maintained by the cam a sufficient length of time to permit the duplicate building-signal to be sent in; but in the final movement the cam is carried out of the path of the projection 67, and the arm 54 is thereby retracted and disengaged from the arm 56 and brought into contact with the arm 57 to send in, through the wheel 60, the floor-signal.

In connection with the instrument I may employ thermal circuit-breakers to produce the break necessary to send a fire-signal, and the floor-section wires and house-wires may be so arranged as to compel a break in the circuit before unlawful entry can be effected. Coincident with the alarm given to the occupants of the affected building, which alarm includes an indication of the location of trouble, the fact of such disturbance and the exact locality of the building are announced to the central office. The instrument, moreover, will indicate the weakening and exhaustion of the battery and will announce through the relay an attempt to render the instrument inoperative by looping out, by which is meant the unlawful attachment of a wire looped around a floor-circuit wire to cut out the circuit.

In practice in the event of a break in the circuit-wire 39 of floor "1," for instance, the magnets 12 12 become deenergized and the armature 11, falling by gravity, effects the release of the clockwork, with the result of rotating the plate 19 until the latter is brought into engagement with the first spring-contact 21. This engagement closes the break between said contact 21 and its companion contact 22, and through wires 23, 35, and 37 and the wires 26, floor-section wires 40 to 43, inclusive, and wire 38 the circuit through the magnets is established and the armature is attracted and moved to check the clockwork, the pointer stopping at "1st floor." In the operation of the released works the circuit in wire 48 is broken by the separation of the

contacts 54 56 and the making of the circuit in which is located the make-and-break wheels 59 60 by the engagements of the contacts 54 57.

I claim as my invention—

1. In an instrument of the class described, the combination of normally closed electric floor-section circuits, a house-circuit connected therewith, a magnet, a spring-actuated train of gearing, an armature normally attracted by said magnet and provided with means normally locking the train of gearing, a circular series of pairs of spring-contacts 70 each pair looped from a floor-section circuit, and a revoluble plate operatively connected with said train to be moved thereby when any one of the floor-section circuits is broken, said plate being movable over the series of pairs 75 of spring-contacts to successively bring the pairs of contacts into maintained engagement to short-circuit the floor-section circuits.

2. In an instrument of the class described, the combination of normally closed electric 80 floor-section circuits, a house-circuit including a double-balanced relay, a normally open circuit looped in the floor-section circuits, an annunciator, a device for successively closing 85 said loops, and maintaining them in closed condition, and means for actuating the annunciator and device adapted to be set in motion by the breaking of one of the floor-section circuits.

3. In an instrument of the class described, 90 the combination of a normally closed electric floor-section circuit, a normally open circuit looped therein, a train of gearing, a device movable by the train when the floor-section circuit is broken to close the loop and maintain 95 a closed circuit, a main-line circuit, and building and floor signal making wheels in the main-line circuit said wheels being successively controlled by the movement of the device.

4. In an instrument of the class described, the combination of a local normally closed electric circuit, means operating through a train of gearing when the circuit is broken for producing and maintaining a short circuit, a 105 main-line circuit, and building and floor signal making wheels in the main-line circuit the wheels being successively controlled by the movement of said means.

In testimony whereof I affix my signature in 110 presence of two witnesses.

ROBERT G. CALLUM.
